(Cl. D61—1)

Fig. 1

Fig. 2

Figure 1 is a top perspective view of an exposure meter, showing our new design; and,

Figure 2 is a bottom perspective view thereof.

The side not shown has substantially the same appearance as the side shown. Portions of the drawing figures are diagonally lined to indicate transparency.

The dominant features of our new design are shown in solid lines in the drawing.

We claim:

The ornamental design for an exposure meter, as shown and described.
